UNITED STATES PATENT OFFICE.

JOHN R. CONNOR, OF FRANKLIN, PENNSYLVANIA, ASSIGNOR OF FIVE-SIXTHS TO CHARLES STRATTON, OF SAME PLACE, CHARLES E. STRATTON, HENRY STRATTON, AND J. C. OSBORNE, OF ERIE, AND J. F. WHITE, OF MEADVILLE, PENNSYLVANIA.

RIVETING-MACHINE.

SPECIFICATION forming part of Letters Patent No. 508,371, dated November 7, 1893.

Application filed June 15, 1892. Serial No. 436,824. (No model.)

To all whom it may concern:

Be it known that I, JOHN R. CONNOR, a citizen of the United States, residing at Franklin, in the county of Venango and State of Pennsylvania, have invented certain new and useful Improvements in Riveting-Machines; and I do hereby declare the following to be a full, clear, and exact description of the invention, such as will enable others skilled in the art to which it appertains to make and use the same.

This invention relates to riveting machines and consists in certain improvements in the construction thereof, as will be hereinafter fully described and pointed out in the claims.

The invention is illustrated in the accompanying drawings as follows:

Figure 1, is a side elevation. Fig. 2, is a front elevation. Fig. 3, is a vertical section on the line 1—1, in Fig. 1. Fig. 4, is a longitudinal section on the line 2—2, in Fig. 2, with the scale increased. Fig. 5, is a fragment of the horn or mandrel A' in like section to Fig. 4, on a still larger scale. Fig. 6, is a transverse section of the horn A' in the line 4—4 in Fig. 4. Fig. 7 is a top or plan view of the horn A' with parts broken away to show construction. Fig. 8, is a perspective view of the rivet conveyer D⁴ of the horn A' removed. Fig. 9, is a side elevation of the rotating rivet hopper L with parts broken away. Fig. 10, is an end view of the hopper L partially in vertical section.

The machine is intended for riveting articles made of sheet metal, leather, canvas, &c., such as stove pipes and other sheet metal tubes, hoops, tin ware, leather and other belting leather and canvas bags or tubes, such as hose and many other like objects.

The machine here illustrated is provided with a long slim horn or mandrel A' and is intended for tube riveting, and can be used on any light objects. Where the work is heavier such as barrel hoops the horn would better be made stronger than is shown in the drawings.

The machine feeds the rivets from the hopper to the point where they are to be riveted

and there first punches the rivet through the material and then upsets or rivets it.

The construction and operation of the machine is as follows, reference being had to the drawings and the letters of reference marked thereon.

A, is the base or column of the machine, 55 and A' the horn, mandrel or anvil, that sustains the rivet and the matter to be riveted, and is preferably cast integral with the column.

A² is the upper frame work or cross arm, 60 with upwardly extending arms A³, A⁴ in which are formed journals a a' of the driving shaft B.

C, is the driving wheel which is loose on the shaft and communicates motion to the 65 shaft through the sliding clutch E, which may be feathered to the shaft and engage the wheel C in any common manner. The clutch E is moved by an elbow lever E' which is operated from a treadle E⁴ in convenient position for the foot of the operator as he stands at the end of the mandrel. The connection between the treadle and the elbow lever is through the rod E³, lever E² which is pivoted at e², and the spring connecting link e⁴. On 70 the vertical end of the elbow lever E' below the yoke which engages the clutch E, there is a sliding block e, and on the wheel C there is a cam c, and below the block e there is a spring e' which holds the block up. When 75 the block is up the cam c will contact with it and throw the lever E' back so as to disengage the clutch. The lever E² at its inner end rests upon a pin on said block, and therefore, when the treadle is depressed the block 80 will be depressed by the lever E², at the same time said lever raises the outer end of the lever E'. Hence when the treadle is depressed the block e is drawn down out of reach of the cam C, and the clutch can engage and keep 85 in engagement with the wheel C; but as soon as the foot is removed from the treadle the block will be pushed up by the spring e' and the cam c will contact with it and disengage the clutch positively and before the shaft can 90 make a full revolution.

The clutch positively and before the shaft can 95 make a full revolution.

On the front end of the shaft B, just outside of the bearing a there is a crank B'. A pitman F connects this crank with a wrist f that extends back from a sliding block F that 5 is guided in ways a^3 a^3 on the front face of the frame work A³. A revolution of the shaft B will, through the crank B', and pitman F cause the block F' to reciprocate vertically. A plunger G is held in lugs on the face of 10 the block F' and is adjustable by nuts g g and in the lower end of the plunger is a riveting bit G². A sleeve G' surrounds the lower end of the plunger and is guided within the lower lug on the block F', and on the lower end of 15 this sleeve are two laterally yielding parts G³ which extend below the riveting die and form a female punch die. At the top of the sleeve G' there is a bridge piece g' which is firmly fixed to the sleeve and extends across it and 20 lies within a slot in the plunger. In the same slot and above the bridge g' there is pivoted at g⁴ an elbow lever G⁴ the depending short arm of which rests on the top of the bridge, and while this lever bears on the bridge the sleeve 25 and plunger will move as one piece, but when the lever is removed from the bridge, as shown by dotted lines in Fig. 3, the sleeve can move up on the plunger, or rather the plunger can move down through the sleeve, and this will 30 occur when the parts G³ are pressed down upon the horn A'. The lever G⁴ is moved at the proper time to allow the sleeve to become free of the plunger by the long or horizontal arm of said lever coming in contact with the 35 lower of two pins a⁴ on the guide a³ and it is moved back again by said arm contacting with the upper of said pins when the plunger moves up. Around the sleeve G' below the block F' and above the pieces G³ is a coiled 40 spring to cause the pieces G³ to exert pressure upon the metal below it after the lever G⁴ has been thrown away from the bridge. After the sleeve has been thus made free from the plunger and the parts G³ are in contact 45 with the metal below them the plunger continues to descend upon the riveting die, passes between the parts G³ and strikes upon the rivet.

The operation of punching and riveting 50 may be herein briefly stated as follows: The object to be riveted lies upon the horn A' below the punching and riveting means, and the rivet is in place upon the horn below the material to be riveted. The plunger descends 55 carrying the sleeve with it and the female punching die G³ is forced down upon the material to be riveted directly above the rivet and thereby the rivet is punched up through the material; at this point the lever G⁴ is 60 tripped off the bridge g' and the plunger G' is free of the sleeve and will continue to descend within the sleeve and the riveting die G² will push aside the parts G³ and press upon and upset the rivet.

65 The means for feeding the rivets into place below the punching and riveting device are as follows: On the cross arm A² of the frame

work, just back of the upright A³ a rivet hopper is located. As illustrated this hopper L is a rotary device and is operated by a belt 75 running over a pulley l on the driving shaft B. I do not intend to be limited to the use of a rotary hopper for there are many forms of feeding hoppers that can be used in this connection. However, I consider my revolving hopper advantageous and preferable and 80 also novel and shall claim the same as new. The hopper L consists of two dish formed disks placed with their concavities facing each other thus forming a hollow disk-formed receptacle. The two parts are placed sufficiently distant from each other to form a circumferential slot, or opening, M around the inner cavity that is of such width as to admit the stems of the rivets which are contained in the hopper. As the hopper revolves the rivets will find their way into the slot M. At intervals there are tangential channels N which are wide enough to admit the heads of the rivets and by these channels the rivets R 85 can escape. At the inner mouths of the channels N there are guards P that prevent the rivets entering the channels except such as have their stems within the slot M. In Fig. 9, an arrow shows the direction of motion of 90 the hopper, and a rivet R is shown as just leaving the outer mouth of one of the tangential channels N. It will there be seen that the rivets in leaving the hopper move by gravity in the opposite direction from that in 95 which the hopper moves. The rivets are prevented from leaving the hopper except when at the proper point of discharge, by gates S that are kept closed by springs s except when the opposite cam-faced ends of the gates come 100 in contact with a block S' and move them back against the action of the springs s. This construction is clearly shown in Fig. 10. On the hopper there are pins O that are located in advance of the gates S. These pins 105 will remove any rivets that may have caught in the mouth of the channel L' before a new rivet is deposited at that point by the hopper. As the rivet leaves the hopper it falls into a vertical channel L'. By observing Fig. 4, it 110 will be seen that the rivets in descending in said channel are intercepted by a worm wheel K' on the vertical shaft K that is actuated by the shaft B through the miter-gears k k', and as this shaft K only revolves when the 115 riveter is in action the passage of rivets past the worm K' will be periodical. To prevent the rivets striking in the channel L' after they have passed the worm a tappet hammer I is made to strike the channel at each revolution of the shaft B by being caught by the catch arm I' that is on a vibrating lever D² and pulled back and then released and allowed to fall by gravity against the channel; a catch i on the hammer I and i' on the arm 120 I' serving to establish the engagement.

In a channel a⁵ on the top of the horn A' there is a reciprocating rivet conveying bar D⁴ having catches d⁴ at intervals thereon.

The rivets R ride on the bar D⁴ with their heads down and stems sticking up through a slot between the two side lips a⁴a⁴. The conveyer bar D⁴ is connected with a sliding block D⁸ that is connected by a rod d⁸ with a vibrating lever D' that is yoked around a cam D on the shaft B and is pivoted above the cam at d to a bracket. The cam D acts to vibrate the lever D' and it in turn reciprocates the block D⁸ and conveyer bar D⁴. Rivets are drawn from the lower mouth of the channel L' by a claw R' (see Figs. 4 and 8) which rides up on a cam r by its arm r' coming in contact with said cam and drops over the end of the cam and back of a rivet, and then as the block D⁸ moves back it passes below the cam r and draws the rivet back with it and places it on the conveyer bar D⁴ in position to be conveyed through the channel on the horn. As the conveyer D⁴ moves forward, the projections d⁴ carry the rivets ahead and when the bar D⁴ moves back the rivets are held against going back by spring dogs H in the side of the channel as seen in Fig. 7. When the rivet reaches position under the riveter it comes against, and its head slips under a holder D⁶ as seen in Figs 5 and 7, most clearly. In Fig. 5, it will be seen that the bar D⁴ has also taken position above the head of the rivet. As soon as the punching operation is completed and just before the riveting is done the holder D⁶ and bar D⁴ are drawn back off the rivet head. The bar D⁴ is drawn back in its ordinary reverse action and the holder D⁶ by a forward movement of a bar D⁵ within the horn A' to which the holder D⁶ is pivoted at d⁶, which movement allows the holder to drop down out of the way, the horn A' being cut away to permit this. See a⁶ Fig. 5. The bar D⁵ is moved by the lever D² that is connected with the lever D' by a link d². The lever D² acts by its heel against a spring d⁵. The bar D⁵ is reacted by a spring d⁷. (See Fig. 4, for the best illustration of this construction.)

What I claim as new is—

1. In a riveting machine, the combination of an anvil for supporting the object to be riveted and the rivet, a reservoir for the rivets, a conveyer in said anvil for conveying the rivets from the reservoir to the point of use, a holder for holding the rivet, a reciprocating plunger acting above and in vertical line with said holder and carrying a female punching die the former being within the latter and a riveting die that act successively upon the rivet first to punch the rivet through the material, and next to upset the protruding end of the rivet and means for operating the moving parts in timely order.
2. In a riveting machine, the combination of a horn or anvil for sustaining the rivet and the article to be riveted, a conveyer in said horn for conveying rivets to the point of use, a holding device in said horn for holding the rivet in place for use, a reservoir or hopper for holding rivets, a feeding device for feed-

ing rivets from the hopper to the rivet conveyer in the horn, a plunger carrying a female punching die and a riveting die that act upon the rivets when in place upon the horn, and proper mechanism for moving the acting parts in timely order.

3. In a riveting machine, the combination of an operating shaft, a driving wheel loose upon said shaft, a clutch operated by a treadle for bringing the shaft into operation from said driving wheel, a reciprocating plunger driven from said shaft, a female punching die carried by said plunger, a rivet feeding mechanism driven from said shaft, a horn or anvil for holding the rivet and article to be riveted and a conveyer in said anvil for carrying rivets to the point of use that is operated from said shaft.

4. In a riveting machine, the combination with the driving shaft, of a vertically sliding block F', the plunger G, carrying die G² and held upon said block, the sleeve G' carried by said plunger and having at its lower end the female punching die G³, the bridge g' on the sleeve G' within a slot in a plunger and the tripping lever G⁴ carried by said plunger and acting upon said bridge.

5. In a riveting machine the combination with the anvil A' of the holder D⁶, the sliding bar D⁵ carrying said holder, the lever D² that moves said bar, and gearing for actuating said lever from the driving shaft B.

6. In a riveting machine the combination with the anvil or horn A' of a rivet way formed in the top of said anvil, extending from the base of the same to its outer end, a conveyer bar D⁴ for moving the rivets in said way, a reciprocating block D⁸ that carries said conveyer bar and gearing for moving said block from the action of the driving shaft B.

7. In a riveting machine, the combination with the horn or anvil A' of a rivet way formed in the top of said horn, a reciprocating bar D⁴ having shoulders d⁴ for moving the rivets forward and spring dogs H for holding the rivets against reaction as the bar D⁴ moves back.

8. In a riveting machine the combination with the horn or anvil that supports the article to be riveted and the rivet, of a channel formed in the top of said horn extending from its base to the outer end a conveyer in said channel for carrying the rivets to the point of use, a hopper for holding rivets and a feeding device for transferring rivets from the hopper to the conveyer in the horn.

9. In a riveting machine, the combination with a rivet conveying channel, of a rotating disk-formed hopper having a peripheral slot, M, for receiving the stems of the rivets and tangential slots, N, for receiving the heads of the rivets.

10. In a riveting machine, the combination with the rotating disk-formed hopper L having discharging channels N and the sliding gates S over the mouths of said channels, of the feeding tube or channel L' and means for

opening said gates as the discharging mouths come opposite the receiving mouth of said feeding tube.

11. In a machine of the class herein shown, 5 the combination with the actuating parts of a hollow, disk-formed, rotating hopper having the interior circumferential channel M, the tangential discharging channels N and movable gates closing the outer mouths of said 10 discharging channels.

12. In a machine of the class herein shown, 15 the combination with the receiving channel

L' and the rotating discharging hopper L of pins O, on the periphery of said hopper, that are in advance of the discharge openings from 15 said hopper, and serve to clear the mouth of the channel L' in advance of the depositing therein of a new rivet.

In testimony whereof I affix my signature in presence of two witnesses.

JOHN R. CONNOR.
